FRAME FOR A DOUBLE DECK SINGLE FACER MACHINE

Hans Meister, Cherry Hill, N.J., assignor to Samuel M. Langston & Company, Camden, N.J., a corporation of New Jersey

Filed Aug. 9, 1965, Ser. No. 86,513

Term of patent 14 years

(Cl. D55—1)

FIG. 1

FIG. 2

FIG. 3

FIG. 4

FIG. 5

FIG. 1 is a side elevational view showing my new design;

FIG. 2 is a top plan view thereof;

FIG. 3 is a rear elevation view thereof;

FIG. 4 is a front perspective view thereof;

FIG. 5 is a rear perspective view thereof.

I claim:

The ornamental design for a frame for a double deck single facer machine, substantially as shown.
